UNITED STATES PATENT OFFICE.

THOMAS DONOHUE, OF TRENTON, MICHIGAN.

MUFFLER.

992,344.

Specification of Letters Patent. Patented May 16, 1911.

Application filed November 4, 1910. Serial No. 590,626.

To all whom it may concern:

Be it known that I, THOMAS DONOHUE, a citizen of the United States of America, residing at Trenton, in the county of Wayne 5 and State of Michigan, have invented certain new and useful Improvements in Mufflers, of which the following is a specification, reference being had therein to the accompanying drawings.

10 This invention relates to mufflers for explosive engines and consists in the matters hereinafter set forth, and more particularly pointed out in the appended claims.

The object of my invention is to make a 15 muffler which will effectually muffle the exhaust of an explosive engine and which shall be cheap to manufacture and easy to assemble, all as more fully hereinafter set forth and shown in the accompanying drawings,

20 in which—

Figure 1 is a vertical central section through a muffler embodying the features of my invention; Fig. 2, a plan view of Fig. 1; and Fig. 3, a section on the line z—z of 25 Fig. 1.

As shown in the drawings A, A' indicate the heads of the muffler, the head A being provided with an internally threaded inlet nipple B and the head A' being provided 30 with an internally threaded boss or outlet C for the exhaust to both of which suitable pipe connections may be made.

D is a sheet metal drum or casing fitting within the standing flanges E on the heads, 35 and F are clamping rods or bolts which clamp the heads A, A' upon the opposite ends of the drum to form a unit structure.

G is a bolt or rod passing through the longitudinal axis of the muffler and upon 40 which is loosely mounted a diffusing member shown herein as a propeller wheel H between the adjustable collars I on the bolt or rod G.

J is an inwardly projecting nozzle forming 45 a continuation of the nipple B and so arranged that the incoming exhaust or spent charge will be directed against the diffuser which will be caused to rotate thereby, and therefore diffuse the exhaust into an opening of larger area than that of the nozzle J.

K is a cone shaped restricting baffle fitting 50 within the drum D and supported on a bracket L adjustably mounted on the rod G, so as to increase or reduce the capacity of 55 the receiving-space between the upper end of said baffle and the underside of the cap A.

The exhaust after being practically diffused into the large opening of the cone-shaped baffle, will then be gradually contracted again and finally be discharged against another spreading device M whereby the exhaust is deflected backward over the outside of the cone-baffle, and which is herein shown as a semi-circular deflector or baffle also adjustably mounted on the rod G and provided with a serrated edge whereby the discharge from the diffuser into the interior of the drum will be rendered less abrupt as compared with the results produced by a solid edge so that the spent charge will be 60 forced by the propeller wheel H through the small end of the cone K, over the serrated edge of the baffle M and out through the nipple C.

N is a suitable drain opening to be used 75 where water is allowed to run into the exhaust pipe, in which case the muffler is to be placed in a horizontal position.

It will thus be seen that a very simple 80 muffler is made which will effectually muffle the charge and which may be readily adjusted to suit the particular requirements. It is also obvious that the muffler may be 85 made of any length by simply using a longer drum and rods or bolts.

What I claim is:—

1. A muffler comprising a casing having an inlet and an outlet, a diffusing member in the casing adjacent the inlet and adapted to diffuse the exhaust passing through the inlet, a restricting baffle having its inlet end adjacent the diffusing member and its outlet end directed toward the casing outlet and a deflector disposed between the outlet end of the baffle and the outlet and having a concave face opposite the outlet opening of the restricting baffle. 95

2. A muffler comprising a casing having an inlet opening and a discharge opening, a rotatable diffusing member adjustable longitudinally of the casing, and adapted to be rotated by the exhaust entering the casing through the inlet, a stationary restricting baffle having a longitudinal opening with a wide inlet adjacent the rotatable member, and also having a restricted outlet discharging 100 toward the casing outlet, and a deflector having a concave face opposing the outlet of the stationary baffle.

3. A muffler comprising a substantially 110 cylindrical casing having an inlet at one end and an outlet at the other, a diffusing wheel

longitudinally adjustable in the casing and adapted to be rotated by exhaust entering through the casing inlet, a conoidal baffle adjustable longitudinally in the casing with its larger end adjacent the diffusing wheel, and a deflector having a concave face opposing the smaller outlet of the conoidal baffle.

1. A muffler comprising a substantially cylindrical casing having an inlet opening at one end and a discharge opening at the other, an axially disposed rod extending through the casing, a diffusing wheel rotatable and adjustable longitudinally on the rod and adapted to be operated by exhaust entering the inlet, a conoidal hollow baffle longitudinally adjustable on the rod with its larger end substantially concentric with the diffusing wheel, and a deflector longitudinally adjustable on the rod and having a concave face opposing the outlet end of the conoidal baffle.

2. A muffler comprising a substantially cylindrical casing having an inlet opening at one end and a discharge opening at the other, an axially disposed rod extending through the casing, a diffusing wheel rotatable and adjustable longitudinally on the rod adapted to be operated by exhaust entering the casing inlet, a conoidal hollow baffle longitudinally adjustable on the rod with its larger end substantially concentric with the diffusing wheel, and a substantially hemispherical deflector adjustable longitudinally on the rod with a serrated edge substantially concentric with the smaller end of the conoidal baffle.

3. A muffler comprising a substantially cylindrical casing, flanged heads closing each end of the casing, rods exterior to the casing for clamping the casing and heads to-

gether, an axially disposed rod passing through the casing and heads, an inlet nipple through one head, an outlet boss in the other head, a diffusing wheel rotatable on the axial rod adjacent the inlet nipple, longitudinally adjustable means on the rod determining the position of the wheel, a conoidal muffler adjustable longitudinally on the axial rod with its larger end fitting the casing concentrically with the wheel, and a substantially hemispherical hollow deflector adjustable longitudinally on the axial rod with a serrated margin substantially concentric with the smaller end of the conoidal baffle.

4. A muffler comprising a substantially cylindrical casing closed at each end and provided at one end with an inlet nipple having a discharge nozzle extending obliquely into the casing, and provided with an outlet at its other end, a diffusing wheel longitudinally adjustable in the casing, and provided with blades against which exhaust entering from the nipple impinges, a conoidal baffle longitudinally adjustable in the casing with its larger end fitting the casing concentrically around the diffusing wheel, and a concave deflector adjustable longitudinally of the casing between the outlet of the latter and the smaller end of the conoidal baffle, and having a serrated margin substantially concentric with the smaller end of the conoidal baffle.

In testimony whereof I affix my signature in presence of two witnesses.

THOMAS DONOHUE.
